DESIGN FOR A COUCH

Arthur F. Breglia, New York, N. Y.

Application March 10, 1939, Serial No. 83,495

Term of patent 7 years

To all whom it may concern:

Be it known that I, Arthur F. Breglia, a citizen of the United States and resident of New York city, in the county of New York and State of New York, have invented a new, original, and ornamental Design for Couches, of which the following is a specification, reference being had to the accompanying drawing, forming a part thereof.

Fig. 1 is a perspective view of a couch, showing my new design.

Fig. 2 is a side elevational view of the same.

I claim:

The ornamental design for a couch, as shown.

ARTHUR F. BREGLIA.
